UNITED STATES PATENT OFFICE.

AUGUST C. DOBRICK, OF CHICAGO, ILLINOIS, ASSIGNOR TO THE IMPERIAL BRASS MANUFACTURING COMPANY, OF CHICAGO, ILLINOIS, A CORPORATION OF ILLINOIS.

MOUNTING FOR WINDSHIELD SPOTLIGHTS, ETC.

Application filed July 17, 1924. Serial No. 726,606.

My invention is concerned with a novel mounting, designed more especially for what are known as wind-shield spot-lights, and is designed to produce a simple structure 5 of the class described than can be cheaply manufactured, and which will maintain the desired degree of friction in the bearing despite its becoming worn, and which does not require any careful adjustment to secure 10 said desired degree of friction.

It is further concerned with such a mounting which, when used for a spot-light, will enable it to be quickly and readily removed from the wind-shield so that it can be used 15 as a "trouble light".

To illustrate my invention, I annex hereto a sheet of drawings, in which the same reference characters are used to designate identical parts in all the figures, of which,—

20 Fig. 1 is a perspective view of my invention as applied to a wind-shield spot-light, with a portion of the wind-shield broken away; and

25 Fig. 2 is a central vertical section through the wind-shield and the mounting secured therein.

I have shown my invention as applied to a wind-shield spot-light in which the customary electric bulb 10 is removably secured in the end of the tube 15, which has the bayonet slot 14, with which the pin 13 on the base of the bulb 10 co-operates. The reflector 12 has the sleeve 12^a which slips on the end of the tube 15 and is secured in place 30 by the set screw 12^b. The tube 15 is associated with a ball mounted in the bearing secured in an aperture 16 in the wind-shield 17. The tube 15 will have a suitable handle 18 brazed or otherwise secured on the end 35 thereof, and said handle has a passage 19 therethrough through which the electrical conductors 20 furnishing the current for the bulb 10 can pass. Any desired switch mechanism can be located in the tube 15, as is customary. It will be observed that the 40 largest portion of the handle 19 is smaller in its dimensions than the internal diameter of the clamping ring 21, so that when the ball is released from the mounting, as hereinafter 45 described, the handle can be passed forwardly through the mounting and the apparatus used for a trouble light for as great a distance as the length of the conductors 50 will permit.

55 The clamping ring or annulus 21 is pref-

erably formed of the radially-extending flange which engages the wind-shield 17 and the axially-extending annular flange 22, which passes through the aperture 16, and which is externally threaded. The ring 21 is provided on its inner periphery with the annular, curved bearing surface 23, preferably shaped to fit accurately on the ball. To clamp the ring 21 securely in place on the wind-shield, I employ the second clamping 60 ring or annulus 24, which is preferably of the same character as the ring 21, and is internally threaded so as to be screwed on the flange 22, and which will preferably be provided with the recesses 25 to which a spanner wrench can be applied for tightening the ring 24 securely to clamp it upon the wind-shield 17. The spherical bearing opposed to the bearing 23 is preferably formed on the inner periphery of the third annulus 26, 70 which preferably fits loosely inside of the annular flange 22, and which is preferably held in place by the annular nut 27 having its periphery milled for easy manipulation, and also having the inwardly projecting flange 28, which will engage the ring 26 and hold the same firmly in engagement with the ball when the ring 27 is screwed on to its limit.

75 The ball is preferably formed of two hemispheres, and one of them, 29, is preferably secured on the tube 15, by brazing or otherwise, and is provided with the annular recess 30 therein. The opposed hemisphere 31 is preferably symmetrical with the hemisphere 29, and differs therefrom only in that it is loosely mounted on the tube 15, so that the strong, helically-coiled expanding spring 32 surrounding the tube 15 and placed in the recesses 30 can operate to expand the ring 80 90 as much as the design of the parts will permit. It will be understood that the spring 32 is stiff enough and of the proper size so that when the ring 27 is screwed up to the fullest extent permitted, the spring 32 will 95 furnish the desired degree of friction between the ball made up of the hemispheres 29 and 31 and the spherical bearing surfaces 23 and 26. By this construction, employing the heavy spring, and properly proportioning the parts 22, 26 and 27, the desired 100 degree of friction to hold the spot-light in any position in which it may be placed can be obtained, and substantially the same friction 105 will always exist, irrespective of any wear 110 that may occur.

The operation of my invention will be readily apparent. By manipulating the handle 18, the rays of the spot-light can be directed anywhere that may be necessary, 5 and it will be held securely in any position in which it is placed. If it is desired to use it as a trouble light, all that is necessary is to unscrew the ring 27, when the spot-light can be pulled out through the opening in the 10 mounting as far as the length of the cord 20 will permit. It will also be noted that while it is so used, the rings 26 and 27, while they are loose upon the spot-light, are confined between the reflector 12 and the hemisphere 15 29, and cannot become lost.

While I have shown and described my invention as embodied in the form which I at present consider best adapted to carry out its purposes, it will be understood that it is 20 capable of modifications.

What I claim as new, and desire to secure

by Letters Patent of the United States, is:

In an apparatus of the class described, the combination with a ball, of a support having an aperture through which the ball extends, a clamping annulus having a radially-extending flange and an externally-threaded axially-extending flange and a curved internal bearing surface, a second clamping annulus, threaded on the first, a third annulus having a curved internal bearing surface, and a fourth annulus threaded onto said axially-extending flange and engaging the third annulus to hold it in contact with the ball, said second, third and fourth annuli all being on the same side of said support and all engaging the first annulus. 25 30 35

In witness whereof, I have hereunto set my hand this 8th day of July, 1924.

AUGUST C. DOBRICK.
